UNITED STATES PATENT OFFICE.

WILLIAM F. MAHONY, OF WASHINGTON, DISTRICT OF COLUMBIA, ASSIGNOR OF ONE-HALF TO LEWIS A. HAWKES, OF CAMDEN, NEW JERSEY.

GOLF-TEE.

1,335,005.

Specification of Letters Patent. Patented Mar. 30, 1920.

Application filed May 6, 1919. Serial No. 295,056.

To all whom it may concern:

Be it known that I, WILLIAM F. MAHONY, a citizen of the United States, residing at Washington, District of Columbia, have invented new and useful Improvements in Golf-Tees, of which the following is a specification.

The present invention relates to improvements in golf tees made of paper or other flexible material and the object thereof is to provide a tee of such construction that a relatively large number thereof may be arranged in a compact package, the individual tees being readily removable and each being adapted to properly support a golf ball.

In the accompanying drawings—

Figure 1 is a perspective view of a golf tee embodying the present invention, the same being shown expanded in position to support a ball represented in dotted lines.

Fig. 2 is an elevation of a sheet consisting of a plurality of the tees, the same being shown in normal collapsed condition.

Fig. 3 is a sectional view on the line 3—3 of Fig. 2,

Fig. 4 is an elevation of a sheet generally similar to Fig. 2 showing a slightly different form of tee.

Fig. 5 is an elevation, and

Fig. 6 an edge view of a book containing a series of sheets each including a plurality of tees, collapsed in a slightly different manner from those shown in the other figures.

Fig. 7 is an elevation of a sheet from which a plurality of tees may be formed in another manner.

Fig. 8 is a sectional view on the line 8—8 of Fig. 7.

Fig. 9 is an elevation of the sheet shown in Fig. 7 folded to form the tees;

Fig. 10 is a sectional view on the line 10—10 of Fig. 9.

Figs. 11 and 12 are respectively an elevation and section view on the lines 12—12 of Fig. 11 of another manner of folding the sheet.

Fig. 13 is a view of a sheet such as that of Figs. 7 to 10 with a plurality of the tees in extended position.

Referring to the drawings it will be seen that my improved tee is formed by two

pieces of paper or other suitable flexible material connected at separated points by any suitable means as an adhesive whereby it is adapted to be expanded into tubular form as shown in Fig. 1, or collapsed to a strip-like form in which condition a series of the tees may be connected to provide a single sheet.

The ends of the members A B of each tee are so united that when the tee is in condition for use, or expanded, it will have two diametrically oppositely arranged outwardly projecting tabs C D which tabs, when the tee is in collapsed form, constitute the ends of the strip. The tabs C are adapted to serve as securing means, such tabs of a plurality of the tees being united by the marginal strip E forming one edge of a sheet while the tabs D may be termed "pulling" tabs, as they afford means by which a person can readily grasp the device and exert a pull to separate the tab C from the strip E.

As shown in the drawings the pulling tabs D are preferably reduced somewhat in width toward their free ends so that the tabs of adjacent tees will be readily grasped separately, and if desired as shown in Fig. 2, the securing or attaching tabs C may be of generally similar form. In this embodiment of the invention the sheet is provided with a series of inclined incisions F extending from the upper edge of each tee so that the actual connection between the tab C and marginal section E of the sheet is relatively narrow.

Instead of making the attaching tabs C in the form shown in Figs. 1 and 2, however, such tabs may be of the full width of the tee blank and to assist in readily detaching each tee from the portion E of the sheet, a series of perforations or indentations G may be provided.

It will be seen that the ends of the members A B are united throughout the length of the tabs C D, the inner lines of the adhesive employed for effecting such connection being represented by dotted lines H in Figs. 2 and 4. As shown it is preferred to make the upper edge of each tee blank of slightly concave form so that the ball will more accurately seat itself. The slight curvature of the lower edge of the tee will adapt it to inequalities in the ground surface

to which it is applied and the outwardly projecting tabs C D also act to impart stability to the tee so that it will not be liable to be easily displaced after once being positioned with the ball thereon. The shape of the tee is such that a player can readily grasp the same while holding a ball in position thereon, and thus simultaneously position them on the ground.

- 10 While the tees may be supplied in separate sheets such as represented in Figs. 2 and 4, it is preferred to combine a plurality of such sheets in book-like form and in order that the width of such a package may 15 be reduced to a minimum, it is preferred to collapse the several tees in the manner illustrated in Figs. 5 and 6. Referring to these figures it will be seen that each of the members A B is folded back upon itself toward 20 the attaching ear or tab C so that when in collapsed form each tee comprises six overlapping layers from which the tabs D project. The lines of folding are approximately mid-way of the distance between the 25 tabs C D and constitute the diametrically opposite angles intermediate of said tabs produced when the tee is expanded into form for use as shown in Fig. 1.

As shown in Figs. 7 to 10, inclusive, the 30 tees are formed from a sheet A' which is initially folded upon itself and connected along two parallels H H by suitable adhesive to provide the extensions or tabs, a line of perforations G being formed between the tee bodies and the section E' of 35 the sheet. The sheet is then additionally folded as shown in Figs. 9 and 10 and the incisions or cuts L required to separate the several tees are then made. As shown in 40 Fig. 9 these incisions extend at a slight angle to the top and bottom edges of the section E' of the sheet whereby when the tees are partially unfolded the upper and lower edges thereof will have a contour 45 such as illustrated in Fig. 13. It will be seen that in this form of the invention the cuts or incisions L dividing the tees one from another extend beyond the line of perforations G. This has been found to 50 assist somewhat in separating the individual tees from the sheet.

Instead of folding the tees so that the pulling tabs D D' are adjacent the outer edges of the leaves or covers of the book-like package in which they are arranged 55 they may be folded so that said pulling tabs D' are arranged approximately mid-way of the width of the sheet, the sections A² B² of the tees projecting in opposite directions 60 from said pulling tabs D. Such an arrangement is illustrated in Figs. 11 and 12.

The manner of using and the advantages of the tee constructed as hereinbefore described, and as shown in the drawings, will

be readily appreciated. It will be understood that the articles may be made of any suitable flexible material, paper being preferably employed because of cheapness and of course there can be modification of the particular embodiments of the invention 7 illustrated without departing from the spirit thereof.

When exerting pull on the tab of any tee in the folded or collapsed form the tee is expanded into form for use and also detached from the body of the sheet.

It will be seen that when in use the ball contacts only with four points on the upper edge of the tee, spaces for free circulation of air being thus provided between the ball and 8 walls of the tee.

Having thus described the invention, what is claimed is:

1. A golf tee comprising a tubular body of flexible material, adapted to be collapsed or expanded, provided with two outwardly projecting tabs or grasping members.

2. A golf tee comprising a tubular body of flexible material, adapted to be collapsed into a strip-like form, provided at diametrically opposite points with outwardly projecting tabs which constitute the ends of the strips when the tee is collapsed.

3. A golf tee formed of paper adapted to be expanded into a tubular body provided with oppositely arranged outwardly projecting tabs or collapsed into a strip-like form with said tabs constituting the ends of the strips.

4. A golf tee formed of folded flexible material permanently united at separated points, whereby sections thereof may be separated to form a tubular body, from which the connected portions will project, or collapsed into a strip-like form, the ends of which are constituted by said connected portions.

5. A golf tee formed of folded flexible material permanently united at separated points, whereby sections thereof may be expanded to form a tubular body, or collapsed into strip-like form, each member being normally folded at an intermediate point in its length to overlie one of the 1 points of connection between said sections.

6. A sheet comprising a plurality of strip-like sections of flexible material each expandable to form a tubular body and normally collapsed into strip-like form with pulling and securing tabs at its ends, all of the securing tabs being united along the inner margin of the sheet.

7. A sheet comprising a plurality of strip-like sections of flexible material each expandable to form a tubular body and normally collapsed into strip-like form with pulling and securing tabs at its ends, all

of the securing tabs being united along the inner margin of the sheet, and the members of each strip being folded upon themselves at an intermediate point whereby the 5 two tabs are brought relatively close together.

8. A sheet comprising a plurality of strip-like sections of flexible material each

expandible to form a tubular body and normally collapsed into strip-like form with 10 tabs of less width than the body of the strips at its ends, all of the tabs at one end of the strips being united.

In testimony whereof I have hereunto set my hand.

WILLIAM F. MAHONY.
